UNITED STATES PATENT OFFICE

GEORGE H. STEPHENS, OF NORTHBROOK, AND ROBERT D. BUDLONG, OF CHICAGO,
ILLINOIS, ASSIGNORS TO THE HAMMOND CLOCK COMPANY, OF CHICAGO, ILLINOIS,
A CORPORATION OF DELAWARE

DESIGN FOR A CLOCK CASE

Application filed September 5, 1931. Serial No. 41,034. Term of patent 14 years.

To all whom it may concern:

Be it known that we, GEORGE H. STEPHENS and ROBERT D. BUDLONG, citizens of the United States, residing at Northbrook and Chicago, respectively, in the county of Cook and State of Illinois, have invented a new, original, and ornamental Design for a Clock Case, of which the following is a specification, reference being had to the accompanying drawings, forming a part thereof.

Figure 1 is a front elevation of a clock case showing our new design;

Fig. 2 is a side elevation thereof; and
Fig. 3 is a plan view thereof.

We claim:

The ornamental design for a clock case, as shown.

In witness whereof, we hereunto subscribe our names this 1st day of September, 1931.

GEORGE H. STEPHENS.
ROBERT D. BUDLONG.
